J. HUBER.
SUBMARINE MINE.
APPLICATION FILED FEB. 12, 1918.

1,314,661.

Patented Sept. 2, 1919.

UNITED STATES PATENT OFFICE.

JAMES HUBER, OF PHILADELPHIA, PENNSYLVANIA, ASSIGNOR TO VICKERS LIMITED,
OF WESTMINSTER, LONDON, ENGLAND.

SUBMARINE MINE.

1,314,661.

Specification of Letters Patent.

Patented Sept. 2, 1919.

Application filed February 12, 1918. Serial No. 216,815.

To all whom it may concern:

Be it known that I, JAMES HUBER, a citizen of Switzerland, residing in the city of Philadelphia, in the county of Philadelphia 5 and State of Pennsylvania, have invented certain new and useful Improvements in Submarine Mines; and I do hereby declare the following to be a full, clear, and exact description of the invention, such as will enable others skilled in the art to which it appertains to make and use the same.

This invention relates to a submarine mine, and this application is directed specifically to subject matter disclosed in my 15 application, Serial No. 173,182, filed June 6, 1917.

The primary object lies in the provision of a mine wherein the sounding ball will be released from the anchor prior to the release 20 of the anchor from the mine itself.

A further object of the invention resides in so constructing the device that the means controlling the release of the anchor from the mine also controls the release of the 25 sounding ball from the anchor.

In the drawing:

Figure 1 is a fragmentary elevation of a mine with a portion of the anchor broken away and with my invention applied thereto, 30 Fig. 2 is a vertical sectional view of the means for securing the anchor to the mine,

Fig. 3 is a sectional view of the sounding ball,

Fig. 4 is a top plan view of the same with 35 the cover removed, and

Fig. 5 is a horizontal section disclosing the manner in which the slide is attached to the connecting element.

As illustrated in the drawing, the mine is 40 secured to the anchor during the launching, and until it reaches a predetermined depth by means similar to that described in my copending application, Serial No. 173,182, filed June 6, 1917.

45 This means includes a cylinder 4, which is pivotally mounted at 5, on an extension 6 of a plate 7. This plate 7 is secured to the side of the anchor 1 in any desired manner and is provided with keepers or 50 guides 8, for the purpose which will later appear. A tubular socket member 9 is screwed into the upper end of the cylinder 4, or is otherwise secured thereto, which socket member acts to close the end of the 55 cylinder. A piston 10 is operable in the

cylinder 4 and is provided with a rod 11 which extends upwardly through the bottom of the socket member 9 and into the same. This rod 11 is provided with a reduced portion 12 and with a head 13, which head has 60 a cam face 14. A connecting element is adapted to extend into the tubular socket 9 and is of inverted U form, having depending legs 15 on the lower ends of which are toe portions 16, which toe portions are 65 adapted to engage within the reduced portion 12 of the rod 11. The connecting element is adapted to be secured to the turnbuckle 17 of the attaching member which passes around the mine. A retaining pin 18 70 passes through apertures in the tubular socket member 9 and through corresponding apertures in the legs 15 of the connecting member. This pin may be of any desired form and material, such for instance 75 as described in connection with the copending application. The inside diameter of the tubular member 9 is such that when the legs 15 of the connecting member are located therein, and the toe portions engage in the reduced 80 portion 12 of the rod 11, the rod and attaching member will move in unison after the initial relative movement, which will occur because of the space which exists between the upper edges of the toe portions 16 and 85 the cam face 14. The piston 10 is provided with an aperture through which fluid contained in the cylinder 4 may pass from one side of the piston to the other. Thus, when the connecting element is disengaged from 90 the rod 11 of the piston, the anchor will be free to move away from the mine. The sounding ball is of the peculiar form illustrated in the drawing, and is provided with fins 19, which cause the ball to descend vertically through the water when it is released from the anchor. This ball is further provided with a chamber 20 which is open at its upper end and in which the desired length of chain 21 is contained, one end of 95 the chain being secured to a hook 22 in the chamber and the other end to the anchor in the usual manner. This chain passes upwardly through a notch 23 in the upper edge of the sounding ball. The links of the chain 100 are so disposed that it will be impossible for the chain to draw through the notch because of the restricted width of the latter. A cover 24 is engaged with the upper end of 105 the sounding ball and is normally main- 110

tained in place by the resiliency of its flanges. Furthermore, this cover is of such material that, when it is detached from the sounding ball, it will immediately sink.

- 5 This sounding ball is supported on the anchor by an arm 25, which has a knob 26 on the end thereof. The arm extends outwardly from the anchor and through an opening 27 in the adjacent side of the sounding ball. As disclosed in the drawing, the relative size of the knob-shaped end of the arm 25 and the opening 27 is such that, upon the swinging movement of the ball outwardly from the anchor, the ball will be 15 disengaged from the arm so that it will then be free to sink. In order that this swinging movement of the ball may be prevented until after the mine has sunk to a predetermined depth, I have provided the 20 following mechanism. A slide 28 is engaged at its upper end with the connecting element above the socket member 9 by being passed over the upper end of said connecting element as illustrated in Fig. 2. This 25 slide is prevented from moving downwardly with relation to the connecting element by projections 29 formed on the legs of said element, and these legs are permitted to move outwardly with relation to each other 30 so as to free themselves from the plunger rod 11, because of the fact that the loop connecting the slide to the connecting element is of greater width than the distance between the legs, so that a slight amount of 35 play is present, as illustrated in Fig. 5. This slide 28 passes through the keepers 8 which have been previously described, and downwardly below the lowermost of the same. The lower end of the slide is bent outwardly 40 from the anchor, as illustrated in Fig. 1, and passes through registering openings in a strap 30, which encircles the lower end of the sounding ball, as illustrated in the drawing. This lower end of the slide also passes 45 through openings which register with the aforementioned openings in the strap, and which are formed in ears 31, which ears extend from the anchor and are secured thereto.
- 50 Thus, it will be seen that before the mine is launched the pin 18 will be withdrawn and after launching, after the mine has sunk to a predetermined depth, the force which tends to separate the mine from the anchor 55 because of the buoyancy of the former,

causes the connecting element to move outwardly from the socket member 9 against the action of the fluid within the cylinder 4. Upon the initial outward movement of this connecting element, the slide 28, which is connected thereto will move sufficiently to withdraw its lower end from the registering openings in the straps 30 and the ears 31. This will release the strap 30 and permit the lower end of the sounding ball to swing 65 away from the anchor and thus be released from the supporting arm 25. This release of the sounding ball takes place before the connecting element has moved sufficiently to pass entirely beyond the end of the socket member 9 or to be disengaged from the rod 11 of the plunger 10.

What I claim is:—

1. The combination with a submarine mine, its anchor and its sounding ball, of a pair of separable elements for securing the mine and anchor together, means for supporting the sounding ball on the anchor, means for securing the sounding ball to the anchor, including a strap which encircles the sounding ball, a slide connected to one of said separable elements, and arranged to hold the strap to the anchor prior to the relative movement of the separable element, but release the strap upon such relative movement.
2. The combination with a submarine mine, its anchor and its sounding ball, of means for detachably securing the mine and anchor together, means for supporting the sounding ball on the anchor, means for preventing the swinging of the sounding ball with relation to the anchor, and means controlled by the first mentioned means for reasonably securing the last mentioned means to the anchor.
3. The combination with a submarine mine, its anchor and its sounding ball, of means for detachably securing the mine and its anchor together, means for supporting the sounding ball on the anchor, but permitting the disengagement of the same upon a swinging movement of the sounding ball, means to prevent said swinging movement, and means controlled by the first mentioned means for controlling the operation of the last mentioned means.

In testimony whereof I affix my signature.

JAMES HUBER.
